INVENTOR

William Gorman

United States Patent Office.

WILLIAM GORMAN, OF NEW BRITAIN, CONNECTICUT.

Design No. 4,160, dated June 21, 1870.

DESIGN FOR A SASH-FASTENER.

The Schedule referred to in these Letters Patent and making part of the same.

Whom it may concern:

it known that I, WILLIAM GORMAN, of New
in, in the county of Hartford and State of Con-
ut, have invented and originated a new Design
ash-Fasteners; and I do hereby declare that the
ing specification, taken in connection with the
ngs making a part of the same, is a full, clear,
xact description thereof.

Figure 1 is a side elevation.

Figure 2 is a top view.

nd B represent the two plates of a sash-fastener,
are respectively secured to the rails of the upper
ower sashes, so that when both sashes are closed,
id plates will be in the same plane. The design
two plates is the same.

e outer edge is surrounded by a raised band or
ng, a, and when the two plates have their con-

tiguous sides lipped, as shown in section at fig. 1, they
will have one common central band line a'.

The space upon each plate not occupied by the screw
holes b, or the segmental raised flange c, is filled in
with leaf work in relief, patterned after the Egyptian
lotus.

The design of the bar C is harmonious in character,
and is clearly shown in the drawings.

What I claim as my invention, and desire to se-
cure by Letters Patent, is—

The design for a sash-fastener, substantially as shown
and described.

WILLIAM GORMAN.
